HAIR WAVING DEVICE

Mervin Wideman, Brooklyn, N. Y.

Application March 2, 1938, Serial No. 193,402

12 Claims. (Cl. 132—32)

This invention relates to an improvement in hair waving devices. The primary object of the invention is to provide a device, more particularly adapted for self-application, but also capable of use in hair-dressing establishments, by which desired waves and ridges may be imparted to the hair simply and effectively.

Various kinds of hair waving devices have been proposed, some of which are damaging to the hair; others are of complex construction and difficult or impossible to use, particularly for self-application, while various other types impart relatively slight wave and ridge formation to the hair. In most cases, the ridge formed in the hair is of unsatisfactory and of artificial appearance, while in other cases a ridge is formed with very little wave formation.

My invention contemplates the provision of a simple, sturdy and automatic hair waver capable of self-application to the hair; which will automatically shift the hairs to impart a natural wave thereto and which will form at least two properly shaped and spaced ridges in the hair.

More particularly, the invention contemplates the provision of several, and at least three, comb-like members connected by pivoted links and provided with manipulating handles by which the combs may be held in spaced-apart relationship while the device is inserted in the hair. When manual pressure on the handles is relieved, spring pressure causes the combs to move toward one another and also relatively endwise, the endwise movement thereof imparting an undulating curvature to the strands of hair engaged by the teeth of the comb, while the movement of the combs toward one another causes the hair strands to be gripped between the sides of the combs and formed with the desired, properly spaced and proportioned, ridges.

In the accompanying drawing, wherein an embodiment of the invention is shown, Fig. 1 is a plan view of a hair waving device made in accordance with the invention, the same being shown in closed or hair-gripping position; Fig. 2 is a plan view of the device in open position; Fig. 3 is a side view of the device; Fig. 4 is a sectional view on the line 4—4 of Fig. 1, looking in the direction of the arrows; Fig. 5 is a transverse sectional view through the comb members indicating how the hair is engaged and embraced therebetween, and Fig. 6 is a sectional view on the line 6—6 of Fig. 3, looking in the direction of the arrows.

In the drawing, 1 indicates the center comb member, and 2 and 3 the side comb members.

These comb members are preferably, but not necessarily, formed of sheet metal. In the embodiment of the invention shown, the center comb 1 includes a top plate 4, which may be perforated or otherwise apertured as shown at 5 to aid in drying of the hair engaged by the device, and is formed with the integral downwardly extending spaced blades 6 and 7. The lower edge of each of the blades 6 and 7 is toothed as at 8, said teeth being inclined as clearly shown in Fig. 3.

Each of the side combs has its lower end toothed as shown at 9, the teeth thereon inclining in a direction opposite to that of the inclination of the teeth 8 on the center comb. Each of the side combs 2 and 3 is formed at its top with a lateral flange 10, serving to reinforce and stiffen the comb and also acting as an anchorage for pivot pins. The side comb 3, at one of its ends, is pivoted at 11 to one end of a link 12, the opposite end of which is pivoted at 13 to the top plate 4 of the center comb. Similarly, the end of the side comb 2 is pivoted at 14 to one end of a link 15 having its opposite end pivoted at 16 to the top plate 4, the pivot 16 being located near the point 13 of pivotal connection of the link 12.

The opposite end of the side comb 2 is pivoted at 17 in a clevis 18 formed on the end of an arm 20 of a bell-crank that is formed with ears 21 which are pivotally mounted on pivot pin 22 secured in an extended end portion or lug 23 of the top plate 4 of center comb 1. The bell-crank is formed with an extended free end 24 constituting a manipulating handle which co-operates with a similar handle 28 for holding the side combs 2 and 3 distended away from the center comb 1 as shown in Fig. 2. Side comb 3 has its end pivotally connected at 25 to the clevis 26 formed on the end of an arm 27 of a bell-crank which has ears 28a pivotally mounted on the pivot pin 22. The bell-crank on which arm 27 is formed is provided with an extended end 28 forming a handle similar to that at 24 on arm 20. A torsional coil spring 29 has ends 30 and 31, one of which bears against one of the arms or handles 24 and 28 tending to hold them apart as shown in Figs. 1 and 6, and hold the side combs 2 and 3 in close proximity to the blades 6 and 7 of the center comb 1. The outer surfaces of the handle portions 27 and 28 are roughened or otherwise irregularly formed as indicated at 32 to facilitate the gripping of these parts by the fingers.

In operation, the hair is moistened or dampened with the usual hair-setting lotion or other dampening medium and the waving device is

held between the fingers by the handles 24 and 28. These handles are squeezed toward one another as indicated in Fig. 2 against the tension of the spring 29, such movement of the handles 5 causing the linkage connection of the center comb with the side combs, consisting of the several links 12, 15, 20 and 27, to move the side combs away from the center comb, to the position shown in Fig. 2. The device in this open 10 position, with the side combs 2 and 3 spaced away from the center comb 1, is now inserted in the hair, and finger pressure on the handles 24 and 28 is then relieved. The spring 29 will cause the side combs 2 and 3 to move inwardly and also 15 longitudinally or endwise of the center comb 1. The longitudinal movement of the side combs 2 and 3 relative to the center comb 1 will cause a wave to be imparted to the strands of hair engaged by the toothed portions 8 and 9 of the 20 respective combs. When the side combs 2 and 3 move inwardly toward the center comb 1, the strands of hair engaged by the combs 1, 2 and 3 will be brought up and embraced between the faces of the combs as shown in Fig. 5 to form 25 the two ridges 33 and 34 in the hair. In other words, the ridge 33 will be formed in the hair by being engaged between the inner face of the side comb 2 and the outer face of the blade portion 7 of the center comb and the ridge 34 will 30 be formed between the outer face of the blade portion 6 of center comb 1 and the inner face of the side comb 3. The blade portions 6 and 7 of the center comb 1 are so spaced apart that there is an intervening dip 35 formed in the hair 35 between the two ridges 34 so that these two ridges are located in properly spaced relationship and impart a natural wave and ridge formation to the hair.

If desired, the central comb 1, instead of being 40 formed in the double-bladed shape shown, may be a single comb similar to the side combs 2 and 3. The center comb 1 is of greater length than the side combs to compensate for the longitudinal movement of the side combs relative to the center comb, so that at no time does any portion 45 of the side combs 2 and 3 extend beyond the toothed portion of the center comb. This will be clear from Figs. 1 and 2 where it will be seen that in the closed position of the device, shown 50 in Fig. 1, one of the ends of each of the side combs lies substantially flush with the free end of the center comb; while in Fig. 2, in the extended position of the device, the side combs have moved longitudinally of the center comb, 55 yet have not had their end portions moved beyond the toothed lower edge of the center comb.

It will also be understood that various modifications may be made in the shape and size of the comb members. The toothed edge of each 60 of the comb members is curved to fit the curvature of the head and if desired, the upper edges of the comb members may be similarly curved as suggested in dotted lines at 36. These and other modifications may be made in the structure without departing from the spirit of the 65 invention.

What I claim is:

1. A hair-waving device comprising a center comb member, and a side comb member disposed 70 on each side of the center member, pivoted links connecting the center comb member with the side comb members, several of said links being provided with projecting end portions forming handles by which the side comb members can be 75 moved away from one another and away from

the center member when said handles are moved toward one another, and spring means for normally holding the side comb members in close proximity to the center comb member.

2. A hair-waving device comprising a center 5 comb and a side comb located on each side of the center comb and substantially parallel thereto, pivoted links connecting the center comb with the side combs, several of said links being pivotally connected and having projecting end portions constituting handle portions by which the side members can be manually moved away from one another and from the center comb and held in separated relationship by manual movement of said handle portions toward one another, and 10 spring means for normally holding the side combs in close proximity to the center comb.

3. A hair-waving device comprising, a center comb, a side comb located at each side of the center comb, spring means for normally holding 20 the three combs in close proximity to one another, a pair of links mounted on a common pivot and each having one end pivotally attached to one of the side combs, the opposite end of each of said links forming a handle for moving one 25 of the side combs away from the center comb.

4. A hair-waving device comprising, a center comb, a side comb located at each side of the center comb, spring means for normally holding the three combs in close proximity to one another, 30 a pair of links mounted on a common pivot and each having one end pivotally attached to one of the side combs, the opposite end of each of said links forming a handle for moving one of the side combs away from the center comb, and 35 against the tension of the spring means when the ends of the links are moved toward one another, said spring means being located at the pivot for the links.

5. A hair-waving device comprising, a center 40 comb of inverted U-shape, a side comb disposed on each side of the center comb and movably connected thereto, said center comb having teeth angularly disposed in one direction, the side combs having teeth angularly disposed in an opposite direction, spring means for holding the combs disposed in close proximity to one another, and handles pivoted on the center comb and connected to the side combs for moving the side combs away from the center comb against the 45 tension of said spring means.

6. A hair-waving device comprising, a center comb, a side comb disposed on each side of the center comb, pivoted links connecting the combs, several of said links having parts constituting 55 handles by which the side combs can be manually moved away from the center comb by movement of said parts toward one another.

7. A hair-waving device comprising, a center comb, a side comb disposed on each side of the center comb and movably connected thereto, spring means for holding the combs in close proximity to one another, and handles pivoted on the center comb and connected to the side combs for moving the side combs away from the center 60 comb against the tension of said spring means when the handles are moved toward one another.

8. A hair-waving device comprising, a center comb, a side comb disposed on each side of the center comb and movably connected thereto, 70 spring means for holding the combs in close proximity to one another, and handles pivotally mounted at one end of the center comb beyond the ends of the side combs and pivotally connected to the ends of the side combs for moving the side 75

combs away from the center comb against the tension of the spring means.

9. A hair-waving device comprising, a center comb, a side comb of less length than the center comb disposed on each side of the center comb and movably connected thereto, spring means for holding the combs in close proximity to one another, the center comb having an extended end portion projecting beyond one end of the side combs, and handles pivotally mounted on said extended end portion of the center comb, said handles each having an end pivotally connected to an end of one of the side combs for moving the side combs away from the center comb against the tension of the spring means when the handles are moved toward one another.

10. A hair-waving device comprising, a center comb, a side comb located on each side of the center comb and movable to and from the same end longitudinally of the center comb, pivoted links connecting the side combs with the center comb, a pivot at one end of the center comb, arms mounted upon said pivot, said arms being connected at one of their ends to the side combs, the opposite ends of said arms comprising handles by which the side combs can be caused to move away from the center comb, and a spring surrounding the pivot and operative against the handles for normally holding the side combs in close proximity to the center comb.

11. A hair-waving device comprising, a center

comb, a side comb located on each side of the center comb and in parallelism therewith and movable to and from the same and also movable longitudinally of the center comb, pivoted links at one end of the side combs for connecting the side combs with the center comb, a pivot at one end of the center comb, arms pivotally mounted on said pivot, each of said arms having an end pivotally connected to an end of a side comb and each arm having an opposite end forming a handle, said handles and arms causing the side combs to be moved longitudinally and laterally of the center comb when the handles are manually moved toward one another, and a spring for normally maintaining the handles in spread-apart relationship to hold the side combs in close proximity to the center combs.

12. A hair-waving device comprising a center comb of inverted U-shape formation, a side comb located on each side of the center comb and movable to and from the same, pivoted links attached at one end to the top of the center comb and attached at their opposite ends to the tops of the side combs, a pair of pivoted arms, the pivot therefor being located at one end of the center comb, one end of each arm being connected to one end of each side comb, finger-engaging means on the arms for moving the side combs relatively to the center comb and spring means for moving said side combs in an opposite direction.
